UNITED STATES PATENT OFFICE.

BERNHARD STADELMAN, OF PITTSBURG, PENNSYLVANIA.

DESIGN FOR A JAR OR BOTTLE.

SPECIFICATION forming part of Design No. 24,383, dated June 11, 1895.

Application filed March 21, 1895. Serial No. 542,726. Term of patent 3½ years.

To all whom it may concern:

Be it known that I, BERNHARD STADELMAN, a citizen of the United States, residing at Pittsburg, in the county of Allegheny and State of Pennsylvania, have invented certain new and useful Improvements in a Design for a Jar or Bottle; and I do hereby declare the following to be a full, clear, and exact description of the invention, such as will enable others skilled in the art to which it pertains to make and use the same, reference being had to the accompanying drawings, which form a part of this specification.

Figure 1 is a view of a jar or bottle, showing my design; and Fig. 2 is a sectional view of the same, these two views being deemed necessary to fully illustrate my design.

The leading feature of my design consists in a bottle or jar having a flared or inclined

front side, a vertical rear side, flared or inclined ends, and rounded corners connecting the front side to the ends.

A refers to the vertical rear side; B, the inclined or flared front side; C, the flared ends connected to the front side by rounded corners; and D, the horizontal top having the neck or collar E.

Having thus described my design, I claim—

The design for a jar or bottle, as herein described and shown.

In testimony that I claim the foregoing I hereunto affix my signature this 9th day of November, A. D. 1894.

BERNHARD STADELMAN. [L. s.]
In presence of—
SAM'L. F. KERR,
JOSEPH LEVIS.
